EX

DESIGN.

C. H. COOPER.

BANNER, &c.

No. 18,598.

Patented Sept. 11, 1888.

UNITED STATES PATENT OFFICE.

CHARLES H. COOPER, OF NEW YORK, N. Y.

DESIGN FOR A BANNER, &c.

SPECIFICATION forming part of Design No. 18,598, dated September 11, 1888.

Application filed June 23, 1888. Serial No. 278,048. Term of patent 14 years.

To all whom it may concern:

Be it known that I, CHARLES H. COOPER, of the city, county, and State of New York, have invented a new and original Design for 5 Banners, &c., of which the following is a specification, reference being had to the accompanying drawing, illustrating the design.

The design presents in its general features a central shield with the field and Stars and 10 Stripes, showing a medallion portrait and a groundwork having one end dark and the remainder of the groundwork light, and an open-work border with fan-shaped fillings at the corners of the groundwork, consisting of light and 15 dark portions.

15 A indicates the banner, having the shield B in the center, with the field and Stars and Stripes, showing a medallion portrait. The edges of the field are formed with a wavy or 20 scalloped border, C, and the top or bottom of the portrait with projections D, substantially resembling spear-heads.

The banner has one end, as at E, provided 25 with a broad dark band extending across the banner, and the rest of the groundwork light, as indicated by F. About the edges of the banner is an open-work border, G, consisting of a series of lines, H, with oval enlargements I, having angular ends J, with enlargements K,

breaking joints with each other. The corners 30 of the banner have fan-shaped fillings K, consisting of a light ground, L, with serrated edges M, and a dark oval border, N, having knob-like projections O and a serrated edge, P, interlocking with the serrated edge M. 35

The general effect of the banner is a dark broad band at one end extending across the banner, with the remaining groundwork light, a shield in the center having the Stars and 40 Stripes and a medallion portrait, and a variegated open-work border extending along the edges of the banner and illuminated fan-shaped fillings at the corners.

I claim—

The design for a banner herein shown and 45 described, the same consisting in a body having an open-work border with fan-shaped fillings at its corners, and a groundwork having its upper end dark, a central shield having a light starred field across its upper end and 50 within the dark end of the body and the part below the field in the light part of the body, and a medallion portrait entirely within the shield below its field, as shown.

CHARLES H. COOPER.
